CANISTER COVER OR THE LIKE

Norman S. Curtis, Indianapolis, Ind., assignor to Harper J. Ransburg Co. Inc., Indianapolis, Ind., a corporation of Indiana

Filed Feb. 7, 1962, Ser. No. 68,706

Term of patent 14 years

(Cl. D44—6)

FIG. 3

FIG. 2

FIG. 1

FIG. 1 is a perspective view of a canister cover showing my new design;

FIG. 2 is a partial sectional view taken on the line 2—2 of FIG. 1; and

FIG. 3 is a sectional view taken on the line 3—3 of FIG. 1.

The dominant features of my design reside in the arrangement in a canister cover having an elliptical handle well whose longitudinal axis is in alignment with that of the cover and a finger grip longitudinally recessed therein projecting above the well and merging into the upper surface of the cover as shown.

I claim:

The ornamental design for a canister cover or the like, substantially as shown and described.
